PHOTOGRAPHIC PRINTING MACHINE

Henry O. Drotning, Rochester, N. Y., assignor
to Eastman Kodak Company, Rochester, N. Y.,
a corporation of New Jersey

Application November 13, 1937, Serial No. 174,423

4 Claims. (Cl. 95—73)

This invention relates to photography and more particularly to platens for photographic printing machines.

One object of my invention is to provide a platen by which a sheet of paper or film may be held into intimate contact with a negative at spaced intervals over its surface. Another object of my invention is to provide a platen with a plurality of resilient fingers which may be differentially compressed in accordance with varying thicknesses of materials, such as printing masks and the like. Still another object of my invention is to provide a platen in which a plurality of resilient fingers are spaced apart in spaced relation with a plurality of orifices, so that any individual protuberance may flex into its corresponding orifice, thereby tending to permit the use of irregular surfaces and at the same time retain printing contact between photographic paper and a negative. Other objects will appear from the following specification, the novel features being particularly pointed out in the claims at the end thereof.

In printing machines, and particularly in printing machines of the larger commercial sizes, even when the best grade of plate glass is used for the printing panels, it is difficult to secure uniform and even pressure over the entire printing area. It is customary to use printing masks of varying thicknesses over parts of the negative and to lay the printing paper over the top of the masks. It is therefore desirable to provide a series of more or less independently resilient projections or fingers for pressing the paper toward the negative over spaced areas.

The present invention is for an improvement over the platen construction shown in U. S. Patent 1,809,238, Roy S. Hopkins, granted June 9, 1931.

Coming now to the drawing wherein like reference characters denote like parts throughout:

Fig. 1 is a fragmentary side elevation partially in section of a printing machine with a platen constructed in accordance with and embodying a preferred form of my invention.

Fig. 2 is an enlarged fragmentary detail section through a portion of a platen constructed in accordance with and embodying a preferred form of my invention.

Fig. 3 is a similar view but of a modified embodiment of my invention.

Fig. 4 is a similar view of still a different modification of my invention, and

Fig. 5 is a fragmentary plan view of a portion 55 of the platen shown in Figs. 1 and 2.

In Fig. 1, I have schematically indicated a printing machine as consisting of a box member 1 having an opening 2 supporting a glass printing panel 3. I preferably provide beneath the glass printing panel, a reflector 4 in which a suitable printing lamp 5 is mounted. With printing machines of this type, it is customary to lay the negative, which is usually a film negative, on the printing panel 3, although if a glass negative is used of the size of the rabbet 6 which supports the printing panel 3, the printing panel may be dispensed with. A platen designated broadly as 7 is used to hold the printing paper in intimate contact with the negative. Such a platen may consist of two parts 8 and 9, part 8 being hinged at 10 to a hinge pintle carried by a slidable bolt 11 and normally held in the position shown by the spring 12. Section 9 is hinged to section 8 by means of a pintle 13 and is preferably provided with a handle 14, so that platen section 8 20 and the platen section 9 can be successively lowered to hold a sheet of paper against a negative for printing.

As thus far described, the printing machine may be of any standard or known construction. This 25 application is particularly directed to the structure of the platen itself.

The platen sections 8 and 9 may consist of rectangular frame members 15 which are covered on their bottom surfaces with relatively rigid 30 plates 16. As indicated in Fig. 5, the plates 16 may be provided with a plurality of apertures 17 which, for convenience, are made circular in shape, as shown in this figure. The platen 16 is preferably relatively rigid, and, if desired, may be 35 made of some transparent material, such as a suitable cellulosic composition. On the bottom of the plate 16, I prefer to attach, as by cementing, a relatively thin sheet of soft resilient material, such as rubber. This sheet of material 40 carries a series of protuberances which are preferably of semi-spherical shape and which are spaced in accordance with the spacings of the apertures 17. Thus, when the rubber sheet 18 has been cemented in place as indicated in Fig. 2, 45 a protuberance 17 will lie directly beneath and preferably in axial alignment with the aperture 17.

I prefer to provide the aperture of a diameter A somewhat greater than the diameter B of the 50 protuberance so that when pressure is applied to the end of the protuberance, it may flex upwardly in to the aperture 17.

In Fig. 3, I show a second embodiment of my invention in which the rubber sheet 18 is pro- 55

vided with protuberances 19 as before, but in this case the apertures 27 do not extend all the way through the platen material 28 and the recess thus formed provides sufficient clearance for the protuberance 19 to flex upwardly as the rubber sheet 18 is stretched at the areas marked S.

I prefer to provide an opening 28 through which air can freely escape as the protuberance flexes into the recess 27. If desired, an air opening 29 can be made through the rubber sheet, although this is not ordinarily desirable because in flexing, the aperture may tend to close.

In accordance with Fig. 4, the rigid platen member 28 may be made of a thin sheet of metal and the apertures 37 may be drilled through the metal so as to permit the rubber sheet to flex as indicated in this figure. In this embodiment of my invention, the rubber sheet 38 is preferably thin and may be provided with protuberances 39 in 20 the shape of truncated cones of smaller diameter than the apertures 37. In extreme cases, it is possible that the rubber sheet 38 will stretch to such an extent that it may project entirely through the apertures 37.

25 With any of the embodiments illustrated above, I can obtain a platen structure in which comparatively light pressure on any one or more of the protuberances will cause the material to flex upwardly into the recesses of the rigid platen member to such an extent that material of varying thicknesses can be readily used for the mask members without at all disturbing the amount of pressure which is actually applied to the various spaced areas of the printing paper. The added resilience and flexibility which is obtained by providing recesses behind each one of the protuberances is very considerable, and it has been found that with this construction, very little pressure is required on the handle 14 of the platen to se- 35

40 cure excellent contact over large negative areas.

What I claim is:

1. In a printing device, the combination with a printing panel, of a platen mounted to move to and from the panel, a series of spaced apertures in the platen, a covering for the platen formed of soft resilient material, resilient projections on said material and spaced to be under the apertures in the platen, said resilient projections being of smaller size than the apertures in the platen and being adapted to flex thereinto. 10

2. In a printing device, the combination with a printing panel, of a platen mounted to move to and from the panel, said platen comprising a member having a substantially plane surface with a series of indentations therein, a rubber covering for said platen including a plurality of projections spaced so that each projection may be opposite to an indentation of the platen and may flex thereinto, each indentation including an air 15 vent. 20

3. A platen for photographic printing machines comprising a plane sheet of rubber with protuberances thereon attached to a plane rigid member, said rigid member including a recess for each protuberance spaced in axial alignment therewith, each recess comprising an opening of larger 25 size than its axially aligned protuberance whereby each protuberance may flex at least partially into said recess. 30

4. A platen for photographic printing machines comprising a plane sheet of rubber with protuberances thereon attached to a plane rigid member, said rigid member including a recess for each protuberance spaced in axial alignment 35 therewith, the size of each aperture being sufficient to receive at least the major part of the protuberance when pressure is applied to the protuberance.

HENRY O. DROTTING. 40
